FUEL BURNING HEATER

Guy L. Welstead, Dixon, Ill.

Application October 13, 1939, Serial No. 299,257

2 Claims. (Cl. 126—360)

The present invention relates to fuel burning heating apparatus, and more particularly to oil burning heaters for water tanks and the like.

It is an object of the invention to provide an improved oil burning heater, simple, yet compact in construction, efficient and reliable in performance, and easy to operate and control.

Other objects include the provision of an oil burner that starts easily, that induces its own draft, that generates its own blast in its flame, that holds its fire in a strong wind and that resists the tendency of down currents near buildings, etc. from reversing its draft, and the provision of a burner that gives complete burning of cheap low grade fuel oils and waste engine oil, and yet is easy to start and simple to regulate.

Still another object is to make a highly efficient heater so that it can be kept a small size, so as to take up little space in a water tank, be light enough for easy handling and installation and to displace so little water in a tank as to submerge by its own weight.

These and other advantages will appear from the following description of one particular embodiment of the invention. The invention resides in certain features of construction, combination of elements and arrangements and proportions of parts, as will be hereinafter particularly pointed out. In the drawing:

Fig. 1 illustrates partly in side elevation and partly in section, a heater constructed according to my invention and particularly suitable for heating watering tanks for live stock;

Fig. 2 is an end elevation partly in section of the same heater; and,

Fig. 3 is an enlarged perspective view partly cut away of the burner cup of the heater of Figs. 1 and 2.

The particular heating device shown in the drawing is made of several lengths of heavy steel pipe welded together. A horizontal flame pipe 10 has a vertical inlet pipe or feed pipe 12 opening into it at one end. The exhaust flues extending from the other end of the flame pipe 10 include vertical and horizontal baffle pipes 14 and 16 and a vertical stack 18. These pipes are all welded together as shown in the drawing to provide a single continuous flue extending down the feed pipe 12, through the flame pipe 10, through baffle pipes 14 and 16 and up the stack 18.

A pair of cross bars 20 welded to the bottom of the flame pipe 10 provide a supporting base for the entire structure. These bars support the flame pipe 10 just far enough off the bottom of a water tank to permit good circulation of water

thereunder, and they are given a small section at 22 where they are welded to the flame pipe to minimize the conduction of heat through the bars 20 to the supporting surface. The particular supporting bars shown are proportioned to properly support the heater in a tank of water or to support it when the heater is used to dry out sand and the like. But when the device is used to heat a building or similar space the flame pipe 10 should be supported much higher off the floor. My heater is constructed of heavy gauge steel pipe and has sufficient weight to hold itself submerged in a water tank, but the supporting bars 20 provide convenient projections over which rocks or other weights or fastenings may be placed for additional security against accidental upset.

An iron burner cup 24, only slightly smaller in diameter than the pipe 12, is welded to a rod 26 and suspended in the pipe thereby from a cross bar 28 laid loose across the top of the pipe 12. A wing nut 30 threaded on the upper end of the rod 26 supports the cup 24 and permits an easy adjustment of its height with respect to the opening into the flame pipe 10. The cross bar 28, being loose, can be shifted to space the suspended cup 24 from the walls of the pipe 12.

The burner cup 24 itself is shown best in the enlarged and partially cut away view of Fig. 3.

30 A flat plate 32 is welded to the bottom of a cylindrical ring 34 and a series of holes 36 are provided below the rim of the cup to aid the burning of the fuel. A wick 38 of asbestos rope is laid in a spiral to cover the bottom of the cup, although very little wick is actually required.

35 A shelf 40 welded to the exhaust stack supports a fuel tank 42. From this tank a fuel pipe 44 leads to the top of the feed pipe 12 and terminates in a downwardly bent portion near the center 40 of pipe 12 to drip oil into the burner cup 24. A valve cock 46 regulates the flow.

To put the heater into operation, the burner cup 24 is lifted out. Its wick 38 is wet with oil and lighted. Then the flaming cup is reinserted 45 in the feed pipe 12 and the wing nut 30 is turned up to lower the cup 24 to the bottom of the pipe. The draft starts most easily when the burner cup 24 is thus lowered. A slight breeze will often create sufficient suction on the stack 18 to start 50 a draft in the right direction to pull the flame through the flame pipe 10, but the operator can aid the correct starting of the draft by cupping his hands over the top of the inlet pipe 12 and blowing into it with his breath. Once started, the draft will maintain itself. After the draft

has started in the right direction, the burner cup 24 should be raised to about the position shown in Fig. 1 and the valve 46 should be opened slightly to start the fuel oil dripping from the pipe 44 into the burner cup 24.

The burner may smoke a bit when first lighted, especially if a large amount of oil has been placed on the wick, but when the excess oil has burned off, and the cup has been raised, the burner builds up a strong blast-like flow of air down past the cup 24 that whips the flame and produces a roar that can be heard in some instances several hundred feet from the burner. I do not understand the reason for the occurrence of the strong blast, but I am confident that the blast is responsible for the strong flame and thorough combustion of my burner and its resulting highly efficient operation. Thus I have found that with the cup 24 in its lowermost position, little or no blast is produced and the flame burns yellow and smoky, but that with the cup 24 raised to somewhat constrict the entrance to the flame pipe 10, the blast builds up quickly and produces a strong blue flame with a soot-less and practically colorless exhaust. The blast invariably accompanies the efficient burning of the fuel and so conveniently serves as the criteria of a good operating adjustment of the position of the burner cup 24, and accordingly the best position for the burner cup can be determined quickly by trial. After the flame and the draft have been started (with the cup 24 in its lowermost position) the cup may be lifted by hand and adjusted by trial to the position giving the best draft. Then the wing nut 30 can be turned down to support the cup there. In such a case the cup 24 should be lowered to weaken the selfgenerated blast effect of the flame. The adjustment is not critical because the cup 24 will hold its flame in a much stronger blast than that required for thorough burning of the fuel. At times it is advantageous to move the cup 24 away from the center of the feed pipe 12 towards the flame pipe 10, by moving the supporting cross bar 28, so as to slightly close the passageway on that side of the cup. Apparently the resulting restriction on the right hand side of the cup 24 as viewed in Fig. 1 tends to compensate for the longer flow path down around the left side.

The intensity of the flame and the rate of heating are controlled by adjusting the opening of the fuel valve 46 to regulate the rate at which the oil drips into the cup 24. The heater develops a good blast and operates efficiently over a wide range of fuel feeding rates, but if the oil is fed too fast the flame begins to burn sooty although it continues to generate a blast. The presence of the soot, of course, indicates incomplete combustion resulting from overloading the burner. As long as this overloading is avoided, the blast and the flame apparently act to keep the cup 24 practically dry because then a change in the setting of the fuel valve 46 produces a prompt corresponding change in the intensity of the flame. Also the wick apparently is unnecessary except for starting, and in some cases I have found burners operating satisfactorily with no wick at all but with only a coating of soot on the cup 24.

A serious operating difficulty with burners of this general type has been the occurrence of "back drafts" or "reversed drafts." Such a condition obtains when the draft becomes established in the wrong direction and carries the flame out the inlet or air-feeding passages. Such

reverse drafts are commonly caused by sudden and temporary wind disturbances such as down drafts on the lee-sides of buildings. In my burner of Fig. 1 a reversed draft not only destroys the blast action and produces a smoky flame, but also directs the flame up the feed pipe 12 and carries most of the heat out into the atmosphere.

I have found that the use of obstruction pipes, such as 14 and 16, providing abrupt corners in the flue passage tends to obstruct the flow of air through the flues and effectively prevents gusts of wind from reversing the draft. I have further found that this construction also reduces the effect of those other gusts that tend to increase the draft and so reduces their tendency to produce a temporary excessive draft that might "pull the fire out." And I have still further determined that the obstruction offered by the obstruction pipes 14 and 16 slows the normal draft of the burner and produces two additional effects: first, the burner is more stable in operation because it is affected less by changes in wind intensities; and second, the burned gases give up their heat more effectively as a result of both of the slower flow of gases and of their impact against the walls of the obstruction pipes 14 and 16 and the stack 18.

Not only have I found that all these desirable effects result from the use of these obstruction pipes, but I have found also that there is a best size and proportion for these pipes so that their effect may appear in the correct amount. Too much obstruction to the draft makes the draft sluggish so that the burner is hard to start, and in extreme cases, it may even impair the blast effect and so cause incomplete combustion. A flue that is too open, that is, has too little obstruction, leaves a draft too sensitive to wind changes and too likely to be blown out or reversed by sudden gusts and down drafts. I have experimented with a large number of sizes, shapes, and proportions of burners, and I have found that the shape and proportions shown in the drawing give the best balance between openness of flue and the baffling effect. These proportions are not extremely critical, but should be maintained substantially as shown if the best results are to be obtained. For example, the drawing is proportioned to show pipes with a five inch external diameter. Thus the length of the flame pipe 10 measured along its center line is twenty-five inches and the obstruction pipes 14 and 16 measured along their center lines are nine and sixteen inches respectively. A reduction of these obstruction pipes 14 and 16 to half of these lengths would make the burner much more sensitive to gusts and sudden down drafts, and an increase to twice these lengths would make the draft more sluggish and the starting of the flame more difficult. A reduction of the pipe size to four inches, without any other change in dimensions would reduce the heating capacity of the burner and make starting a little less easy, but nevertheless would leave the burner with a good draft performance. A further reduction to a three inch diameter would make the draft sluggish and very difficult to start. An increase in the diameter from five to six inches would not materially change the draft characteristics. Of course, when it is desirable to use a small diameter pipe in a particular installation the other dimensions may also be reduced the proper amounts to give the device the desired balance between openness of flue and the baffling effect.

Naturally, a long narrow passage tends to "pocket" cold air and so make starting difficult, and in general either increasing the diameter or reducing the length will make starting easier.

I have found it best to use a burner of the proportions shown for practically all stock tank installations, and to provide extension stacks or other artifices where down drafts have been unusually strong and troublesome, as by extending the stack above the roof of nearby buildings. In fact my construction has proven so effective, that conventional "dampers" of the butterfly valve type are never necessary, and actually when such dampers have been installed in extension stacks the users of my heaters have always operated those dampers in fully open position. The adjustment of the position of the flame cup 24 not only provides all the regulation necessary for obtaining the best operation of the heater, but apparently also provides, in cooperation with my flue construction, an adjustment of the flue obstruction et cetera, over a wide enough variation and within the proper range of valves to meet the requirements of most wind conditions and the like.

The closely spaced abrupt turns in the flue of my burner are particularly effective for protecting the fire against disturbing wind conditions because they impose a greater check on disturbances from gusts and sudden wind changes than they impose on the starting of the draft and its normal steady flow. Thus a straight flue designed to provide the same ease of starting and normal draft would provide less protection against gusts and down drafts.

I have found that my oil burning heater is highly efficient in operation and that it requires less fuel than competing devices or other known oil burners for heating a water tank of the same size. Furthermore, my heater has a greater heating capacity and so will keep a larger tank thawed out than will others of the same size. My device is extremely small and compact and accordingly light in weight, and yet it is heavy enough compared to its size that it sinks in water and remains submerged while in operation without the aid of rock or other weights.

My burner is extremely simple to regulate,

easy to start and convenient to operate. It is adjustable over a wide range to accommodate different wind conditions. It resists wind disturbances, and burns clean and heats effectively in spite of changing or gusty wind conditions. It is simple in construction and having nothing to get out of order, is dependable in operation.

It will be apparent to those skilled in the art that my invention is not limited to the specific embodiment herein illustrated and described by way of example, but that it is capable of numerous modifications and variations and is to be limited only within the scope of the appended claims.

I claim:

1. In combination, a down draft flue, opening at its bottom into another flue extending laterally out the side thereof, a flame cup in said down draft flue, adjustable suspension means for supporting it therein near the opening and for adjusting it up and down between a position alongside said side opening and a point thereabove, said cup being of such size and construction that when raised above said outlet opening it offers considerable obstruction to flow of gas down said flue, but when lowered it uncovers at least a part of said opening out the side of said down draft flue to reduce the obstruction, and means for maintaining a flame on top of said flame cup.
2. In combination, a down-draft flue, a flame generator obstructing the flue but providing substantial down draft flame passages all around said flame generator, means for dripping liquid fuel on the top of said flame generator, a flame chamber opening out the side of said down draft flue, means for adjustably supporting said flame generator centered in said flue near said opening, whereby the flame generator may be adjusted up and down to cover and uncover said opening out the side of said down draft flue and may be brought thereby to the position at which the flame burns with a strong blast and whereby also the spattered and atomized fuel rebounding from the top of said flame generator is caught by the down draft on all sides of said flame generator.

GUY L. WELSTEAD.
